UNITED STATES PATENT OFFICE.

ANDREW J. TALLEY AND WILLIAM B. TALLEY, OF BELL POINT, OHIO.

GRINDING-MILL.

SPECIFICATION forming part of Letters Patent No. 593,823, dated November 16, 1897.

Application filed May 21, 1897. Serial No. 637,636. (No model.)

To all whom it may concern:

Be it known that we, ANDREW J. TALLEY and WILLIAM B. TALLEY, of Bell Point, in the county of Delaware and State of Ohio, have invented certain new and useful Improvements in Grinding-Mills; and we do hereby declare the following to be a full, clear, and exact description of the invention, such as will enable others skilled in the art to which it appertains to make and use the same.

This invention relates to improvements in grinding-mills, and has more particular relation to mills for grinding or reducing middlings.

15 The invention consists of certain novel constructions, combinations, and arrangements of parts, all of which will be hereinafter more particularly set forth and claimed.

In the accompanying drawings, Figure 1 represents a perspective view of the devices embodying our invention. Fig. 2 represents a central vertical section through the same. Fig. 3 represents a vertical transverse section of said devices on the line $\alpha\alpha$ of Fig. 1. Fig. 4 represents a vertical transverse section through said devices on the line $\gamma\gamma$ of Fig. 1, and Fig. 5 represents an enlarged detail perspective view of the feeding and grinding screw.

30 1 in the drawings represents the containing-casing; 2, the feed-hopper; 3, the feeding and grinding screw; 4, the movable pressure-block, and 5 the operating-handle.

The casing 1 may be constructed of any desirable material and comprises a base-plate 6 and side and end walls 7 and 8, respectively. Said casing 1 is provided internally with a plurality of vertical longitudinal partitions 9, forming a feeding-trough 10. These partitions do not extend the full length of the casing 1, but terminate some distance from one end of the same, at which point they are connected by an end piece 11, having a circular aperture 12 formed therein and provided with a flange 13, which forms a shallow rectangular chamber 14 about said aperture. The base of said casing is formed with a discharge-opening 15, which lies immediately below the forward end of the flange 13, so that the middlings discharged from the same will fall through said opening into a

suitable chute or receptacle arranged below said opening.

The feed-hopper 2, which may be of any desired construction, is preferably formed, as shown, of two transverse partitions 9, connected by any suitable longitudinally-inclined partition and mounted in the casing 1, so as to discharge into the rear end of the feeding-trough, the forward portion of said feeding-trough being closed by a top plate 16. The pressure-block 4 is suitably hinged to said plate 16, so that it normally hangs suspended against the flanges 13 and thus closes the chamber 14. This block is provided with a pressure-handle 17, which extends through a suitable vertical slot 18, formed in the end of the casing, and is provided with an adjustable weight 19, whereby the pressure of said block may be regulated at will. Said screw 3 is journaled at one end in the casing 1, so as to project longitudinally through the trough 10. The projecting journal end of said screw is preferably squared, as at 20, for the application of the operating crank-handle 5. If so desired, a suitable belt-wheel may be applied to this end of the journal-shaft in lieu of the crank-handle, so that the device may be operated by any suitable power mechanism. The forward end of the screw is supported by resting within the circular aperture 12, formed in the end block 11. The metal forming the screw is bent at its forward end, so as to lie in planes extending at right angles to the axis of the screw. This end portion of the screw is roughened or corrugated, so as to present a grinding surface for reducing the middlings to the proper consistency, which reduction or grinding is caused by the rotation of the end of the screw in proximity to the pressure-block 4.

It will be observed from the foregoing description that the middlings or other grain placed in the hopper 2 will pass therefrom into the trough 10 and from thence will be fed forward by the rotation of the screw 3 until they reach the forward end of the trough, when they will pass through the aperture 12 and into the shallow chamber 14. The roughened ends of the screw will then force the grain or middlings against the surface of the pressure-block 4 and reduce or pulverize the

same. When the chamber 14 becomes filled with pulverized material, the pressure caused therein by the continued feeding of the screw 3 will cause the pressure-block 4 to turn upon its hinges and permit the pulverized material to escape through the aperture 15 in the bottom of the casing. By this means the grain is properly ground upon reaching the end of the screw and then discharged from the machine, said operation taking place while fresh grain is being discharged from the hopper into the trough and fed forward by the screw, so as to be forced in turn against the pressure-block and reduced to the proper degree.

15 The degree of fineness to which it is desired to reduce the grain or middlings may be regulated at will by adjusting the weight 19 back and forth upon the lever or arm 17. Should the grain at any time become choked in the chamber 14, so as to interfere with the action of the screw 3, the hinged pressure-block 4 will immediately yield against the influence of the weight 19 and thus permit the excess of material to escape from the chamber. By 25 the peculiar construction of the end of the screw the grain which has been fed through the trough is drawn onto or between the roughened end of said screw and the pressure-block by a wedging action, the pressure of 30 which gradually increases as the screw revolves until the grain is crushed and pulverized by contact with the roughened or corrugated portion.

We preferably close the top of the casing 1 by a cover 21, formed with an opening 22, which latter is located directly above the mouth of the feed-hopper, so that the grain or middlings may be readily placed in the same.

40 The construction of the machine is very simple and cheap, but at the same time very effective, as the grain has simply to be placed into the hopper 2 and the screw rotated to effect the speedy reduction or pulverization 45 of the same.

We do not wish to limit ourselves to any particular construction of conveying-screw, as any one of the different types of Archimedean screws may be employed with equal facility.

50 It will be observed from the foregoing description that the middlings fed forward through the trough by the screw will be jammed into the space between the end of the screw and the yielding block and will thus be crushed or pulverized to any desired degree of fineness, according to the adjustment of the weight upon the pressure-arm.

We further do not wish to limit ourselves 60 to a roughened end of the grinding-screw, as the grinding action may be effected with a smooth as well as a rough construction. This mill is particularly desirable in the reduction of middlings, because of the peculiar rubbing 65 action which occurs between the particles of the grain, the end of the screw, and the pressure-block. This peculiar grinding action

cannot be secured by rolls in which the grain is simply mashed, and therefore said grain cannot be reduced to the consistency of grain 70 passed through a machine constructed according to this invention. In fact a saving of fully twenty-five per cent. of flour from the "feed" usually left by grinding-rolls may be accomplished by this machine with its peculiar 75 rubbing and grinding action.

Having thus described our invention, what we claim as new, and desire to secure by Letters Patent, is—

1. In a grinding-mill, the combination with 80 a suitable casing, of a rotatable feeding and grinding screw mounted in the same and having a grinding end, a movable pressure-piece mounted in proximity to the grinding end of said screw, and devices for holding said pressure-piece in such position with a yielding pressure whereby the grain is forced between said grinding end and said pressure-piece, substantially as described.

2. In a grinding-mill, the combination with 90 a suitable casing, of a rotatable feeding and grinding screw mounted in the same and having a roughened or corrugated grinding end, a movable pressure-piece mounted in proximity to said grinding end, and devices for holding said pressure-piece in position in relation to said grinding end with a yielding pressure, substantially as described.

3. In a grinding-mill, the combination with 100 a suitable casing, of a feeding-trough mounted therein, a rotatable feeding and grinding screw mounted in said trough and having a grinding end, a movable pressure-piece adapted to normally lie in proximity to said grinding end and contact with the end of said trough, and devices for holding said pressure-piece in position with a yielding pressure, substantially as described.

4. In a grinding-mill, the combination with 110 a suitable casing, of a rotatable feeding and grinding screw mounted in the same and having a grinding end, a movable pressure-block mounted in proximity to said grinding end, and a weight mounted on said pressure-block and adapted to normally hold it in proximity 115 to said grinding end with a yielding pressure, substantially as described.

5. In a grinding-mill, the combination with 120 a suitable casing, of a feeding and grinding screw mounted therein and having the metal forming the same bent at one end at right angles to the axis of the screw and roughened or corrugated, a movable pressure-block engaging the end of said screw and means for forcing said pressure-block into engagement 125 with said screw under a yielding pressure, substantially as described.

6. In a grinding-mill, the combination with 130 a suitable casing, of a feeding-trough mounted therein, an end block mounted in one end of said trough and formed with a circular opening and a shallow chamber outside of said opening, a feeding and grinding screw mounted in said trough so as to project

through the circular opening, a pressure-block adapted to engage the end of the end block to close the shallow chamber therein and also the end of the screw, and means for forcing 5 said pressure-block into engagement with the screw and end block under a yielding pressure, substantially as described.

7. In a grinding-mill, the combination with a suitable casing, of a rotatable feeding and 10 grinding screw mounted in the same and having a grinding end, a hinged pressure-block mounted in proximity to said grinding end,

and a weight mounted on said block for holding it in place in proximity to said grinding end with a yielding pressure, substantially as 15 described.

In testimony whereof we have signed this specification in the presence of two subscribing witnesses.
